(57) **CLAIM**

The ornamental design for a sensor opening trash bin with lid, as shown and described.

DESCRIPTION

FIG. 1 is a front view of a sensor opening trash bin with lid showing my new design.

FIG. 2 is a left side view of FIG. 1, the right side view being a mirror image of the left side view.

FIG. 3 is a top view of FIG. 1.

FIG. 4 is a rear view of FIG. 1.

FIG. 5 is a bottom view of FIG. 1.

FIG. 6 is a side and top perspective view of FIG. 1.

FIG. 7 is a side and top perspective view of the sensor opening trash bin of FIG. 1 shown without the lid; and, FIG. 8 is a side and top perspective view of the lid of the sensor opening trash bin of FIG. 1.

The trash bin and the lid are being shown separated in FIGS. 7 and 8 for convenience of illustration.
